UNITED STATES PATENT OFFICE.

JOSEPH J. SCHLAEGER, JR., OF ST. PAUL, MINNESOTA.

DIRECTIONAL SIGNAL.

Specification of Letters Patent. Patented Feb. 20, 1917.

1,217,075.

Application filed February 11, 1916. Serial No. 77,660.

To all whom it may concern:

Be it known that I, JOSEPH J. SCHLAEGER, Jr., a citizen of the United States, residing at St. Paul, in the county of Ramsey and State of Minnesota, have invented new and useful Improvements in Directional Signals, of which the following is a specification.

This invention relates to directional signals for all kinds of motor vehicles, the object of the invention being to produce a signal of the character referred to, the construction of which adapts the same to be readily mounted upon any motor vehicle and operated by the driver in his seat, the mechanism involving front and rear signaling devices shown in the form of semaphores, both of which are coupled to the same actuating shaft and simultaneously operated by a common lever for the purpose of advising persons and the drivers of vehicles in front and in rear of the machine as to any contemplated change in the direction about to be taken by the machine equipped with the signaling apparatus.

With the above and other objects in view, the invention consists in the novel construction, combination and arrangement of parts, as herein described, illustrated and claimed.

In the accompanying drawings:

Figure 1 is a side elevation of a sufficient portion of a motor vehicle to illustrate the application of the signaling apparatus of this invention thereto.

Fig. 2 is an enlarged vertical longitudinal section showing the forward portion of the signaling mechanism.

Fig. 3 is a similar view showing the rear portion of the signaling mechanism.

Fig. 4 is a front elevation of a sufficient portion of the vehicle to illustrate the relation of the signaling apparatus thereto.

Fig. 5 is a rear elevation of a sufficient portion of a motor vehicle to illustrate the relation of the signaling apparatus thereto.

Fig. 6 is a detail perspective view of the front shaft hanger as applied to what is termed a square axle.

Fig. 7 is a similar view of the front shaft hanger as adapted for use in connection with a round axle.

Fig. 8 is a detail perspective view of the rear shaft hanger.

Fig. 9 is a perspective view of one of the clips for fastening the rear hanger support to the rear axle housing.

Fig. 10 is a detail view of the operating lever.

Fig. 11 is a plan view of the lever retaining rack.

Referring to the drawings, 1 designates the front axle of a motor vehicle, 2 the rear axle housing thereof, 3 the floor of the vehicle, 4 the radiator, 5 the shaft of the engine starting crank, 6 the front wheels and 7 the rear wheels of the machine, all of said parts being of the usual construction and arrangement.

In carrying out the present invention, I employ a signal actuating rock shaft designated generally at A and comprising a front section 8 and a rear section 9, the said shaft sections being arranged in longitudinal alinement with each other and extending longitudinally and about centrally of the chassis. The adjacent extremities of the shaft sections 8 and 9 are connected in fixed relation to each other by means of a T coupling 10 of tubular formation having the horizontally extending portion 11 to receive the adjacent ends of the shaft sections 8 and 9 and an upstanding portion 12 adapted to receive the lower end of an operating lever 13 which extends through the floor 3 of the vehicle and is provided beneath the floor with an offset portion 14 adapted to clear the drive shaft of the machine so as to enable said lever 13 to be swung to one side or the other of the machine for a purpose which will appear.

The lever 13 passes through an opening in the floor 3 and to said floor is secured a rack 15 shown in the form of a plate secured to the floor by fasteners 16, the plate extending transversely of the machine and being provided with a longitudinal slot 17 having extensions or notches 18 and 19 into which the lever 13 is adapted to be drawn by means of a lever retaining spring 20 one end of which is attached to the lever 13, the other extremity of the spring being attached to the floor 100 or other convenient part of the machine at the point 21.

At its forward extremity the rock shaft A is provided with an upstanding arm 22 carrying a signal or semaphore 23 and at its rear end said shaft A is provided with another upstanding arm 24 carrying a semaphore or like signal 25. The arms 22 and 24 are in line with the operating lever 13 so that when said lever stands in an upright 110

position, the semaphore arms 22 and 24 also assume an upright position. When the lever 13 is swung to one side or the other, the arms 22 and 24 are turned in a corresponding direction as all of said parts have a fixed relation to each other.

The rock shaft A is supported adjacent to its forward end by means of a front shaft hanger designated generally at B and is supported adjacent to its rear end by a shaft hanger designated generally at C. As shown in Fig. 6, the front shaft hanger embodies a pair of L-shaped bearing members 26 arranged in spaced relation to each other and formed with bearing openings 27 for the shaft A. The bearing members 26 are provided with oppositely extending flanges 28 through which are inserted bolts 29 arranged in front and rear of the axle 1, said bolts also passing through a cap plate 30 which is slotted as shown at 31 to allow for adjustment to suit axles of different sizes. Bolts 32 are also inserted through the spaced bearing members 26 as shown. By the means just described, the shaft hanger as a whole is held in fixed relation to the front axle 1.

In case the front axle is of the round type, the shaft hanger illustrated in detail in Fig. 7 is employed, the same comprising the split sleeve 33 having outwardly extending flanges 34 to receive clamping bolts 35 by means of which the sleeve 33 is tightly clamped around the front axle. The hanger shown in Fig. 7 comprises the bearing members 36 arranged in spaced relation to each other and secured to the sleeve 33 by fasteners 37, said bearing members being provided with bearing holes 38 to receive the rock shaft A. In order to prevent longitudinal movement of the shaft A, a stop collar 39 is adjustably fastened on said shaft by means of a set screw 40 or the equivalent thereof, said collar being located between the spaced bearing members 26 or 36 as the case may be.

The rear shaft hanger C also comprises a pair of spaced bearing members 41 which are preferably connected together at the bottom as shown at 42 and provided with bearing openings 43 for the shaft A. The members 41 are extended as shown and outwardly offset to provide substantially semi-cylindrical portions 44 to embrace a hanger support 45 shown in the form of an inverted arch or bow secured to the rear axle housing. The members 41 are further provided with flanges 46 to receive clamping bolts 47 by means of which the bearing members 41 are fixedly clamped to the support 45.

The opposite extremities of the shaft hanger support 45 are preferably flattened and provided with holes 48 to receive bolts which are inserted through diametrically split sectional clips 49 which embrace the

rear axle housing 2 as shown in Fig. 5, the support 45 being thus fixedly connected to the rear axle housing.

The arm 22 at the forward end of the shaft A is provided with an eye or loop 50 to embrace the shaft 5 of the engine starting crank in order that the arm 22 may be thrown the necessary distance to one side or the other. While this eye or loop 50 is shown as of circular formation, it will, of course, be understood that the shape thereof may be changed in any way that will permit the arm 22 to swing laterally to the desired extent.

From the foregoing description, taken in connection with the accompanying drawings, it will now be understood that when the lever 13 stands in an upright position, being sustained in such position by means of the spring 20 and the central notch 18 of the rack 15, the semaphore arms 22 and 24 will also stand in an upright position, this being the neutral or non-signaling position. If the operator of the machine intends to turn to the right, he presses the lever 13 to the right, the spring 20 permitting the lever to move out of the notch 18 and again causing said lever to be retained in the right hand notch 19 when the latter is reached by the lever. In this movement of the lever 13, the front and rear signaling arms are swung in a corresponding direction so that the front and rear semaphores will point to the right thereby indicating to those in front and rear of the machine the contemplated change in the direction of the machine. While it is preferred to arrange the lever 13 low down so that it may be pushed or kicked from one position to another by the foot of the operator of the machine, said lever may, of course, be made of sufficient length to be operated by the driver's hand. It is also preferred to make the lever 13 of sectional construction so that the upper portion thereof may be separated from the lower portion at a point just above the floor 3 where the upper and lower portions of the lever are shown as detachably connected together by a threaded joint 51.

Having thus described my invention, I claim:

In a directional signal, the combination with a motor vehicle, of a sectional rock shaft extending longitudinally of the chassis and beneath the vehicle body and the front and rear axles, hangers for said shaft fastened to the front and rear axles, each embodying a plurality of bearing members in spaced relation to each other, a stop collar on said shaft between two adjacently located bearing members, arms rising from the front and rear extremities of said shaft and located respectively in front of the front axle and behind the rear axle, a semaphore carried by each arm, an operating lever ex-

tending through the vehicle floor and offset
between its ends to clear the drive shaft,
a tubular T-coupling receiving and fixedly
connecting the adjacent extremities of the
5 rock shaft and the operating lever, and a
rack for holding said lever in any one of
several positions.

In testimony whereof I affix my signature
in presence of two witnesses.

JOSEPH J. SCHLAEGER, JR.
